DESIGN FOR A CLOTHESPIN

Alfred M. Jacobson, Houston, Tex.

Application February 3, 1945, Serial No. 117,740

Term of patent 14 years

(Cl. D17—6)

To all whom it may concern:

Be it known that I, Alfred M. Jacobson, a citizen of the United States, residing in the city of Houston and county of Harris and State of Texas, have invented a new, original, and ornamental Design for a Clothespin, of which the following is a specification, reference being had to the accompanying drawing, forming a part thereof.

I claim:
The ornamental design for a clothespin, substantially as shown.

ALFRED M. JACOBSON.
